UNITED STATES PATENT OFFICE.

IRVIN A. SCRIBNER, OF SAN DIEGO, CALIFORNIA.

BURNISHING-TOOL.

1,171,146.

Specification of Letters Patent.

Patented Feb. 8, 1916.

Application filed January 9, 1914. Serial No. 811,261.

To all whom it may concern:

Be it known that I, IRVIN A. SCRIBNER, citizen of the United States of America, residing at San Diego, in the county of San Diego and State of California, have invented certain new and useful Improvements in Burnishing-Tools, of which the following is a specification.

This invention relates to a burnishing tool particularly adapted for use in transferring engravings although it may be used for other purposes when desired, such for instance, as for restoring the gloss to paper which has been roughened by erasures and the like.

The object of the invention is to provide an improved tool of this character which will efficiently transfer an impression from one article to another when the engraving to be transferred is rubbed with the tool.

Further objects and advantages of the invention will be set forth in the detailed description which now follows.

In the accompanying drawing, Figure 1 is a side elevation of a tool constructed in accordance with the invention, Fig. 2 is a lateral sectional view therethrough, and Fig. 3 is a detailed sectional view illustrating a slightly modified form of the invention.

Like numerals designate corresponding parts in all of the figures of the drawing.

Referring to the drawing, the numeral 5 designates a tubular body carrying a head 6, that is provided with a rounded upper face 7, adapting this portion of the tool to be likewise used for burnishing or transferring, when desired. The head may be made in one piece with the tube, or it may be separately formed and provided with a plug 8, soldered or otherwise secured in the tube. The lower end of the tube 5, is spun inwardly at 9, to cause it to retain a ball 10, so that the ball is capable of rotation in the lower end of the tube. This ball is held against movement into the tube by a curved plate 11, which plate in turn is held in place by a filling 12. This filling may be put in place as a plastic material which afterward hardens.

In the modified form of the device, illustrated in Fig. 3, the tube 5^a is provided with the filling 12^a which retains in position a plate 11^a and the ball 14, is disposed in the

mouth of the tube and is held in place by 55 ball 13. The lower end of the tube is spun inwardly at 9^a, to prevent the movement of ball 14 out of the tube.

In use, balls 10 or 14 are rubbed over the sheet, the impression upon which is to be 60 transferred. The rolling of the ball permits such action without danger of tearing the sheet. It is of course, apparent that the smaller the surface actually contacting with the sheet, the more effective will be the 65 pressure at that particular point, however, if it were attempted to use anything in the nature of a pointed burnisher, the sheet would certainly be torn, but by making the contacting member a rotative one it is possible to use this relatively small contact surface and still secure the desired results. 70

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claim. 80

Having described my invention, what I claim is:

A device of the character described comprising a tubular body portion, a ball mounted in the lower end thereof with a portion of its periphery projecting from said body portion, said tube being partially spun over said ball to retain said ball, a plate comprising a section of a hollow sphere seated in said tubular body portion and backing up said ball, a cap closing the upper end of said tubular body portion and a body of filling material of such a nature that it is plastic when placed in position and afterward hardens, said filling material completely filling the space between said plate and said cap to thereby hold said cap 100 in engagement with said ball.

In testimony whereof I affix my signature in presence of two witnesses.

IRVIN A. SCRIBNER.
